FIG. 6

FIGURE 1 is a perspective view of my design for a portable radio shown in an open position, the cross-lined shading being indicative of grille portions having a large number of uniformly spaced miniature perforations;

FIGURE 2 is a top view thereof;

FIGURES 3, 4, and 5 are side, top and front views respectively of my design shown in a closed position and with FIGURE 5 having a portion of its front cover broken away to better illustrate the grille configuration therebelow; and

FIGURE 6 is an enlarged fragmentary perspective view showing in detail the perforated grille portions represented by cross-lined shading in FIGURES 1, 2 and 5.

Portions of the drawing are stippled to indicate contrast in appearance. The legible matter has been broken for illustrative purposes only.
